US00D962905S

(12) **United States Design Patent** (10) **Patent No.:** **US D962,905 S**
(45) **Date of Patent:** **** Sep. 6, 2022**

(54) **DEVICE CONTROLLER**

(71) Applicant: **Magic Leap, Inc.**, Plantation, FL (US)

(72) Inventors: **Shigeru Natsume**, Weston, FL (US);
Sebastian Gonzalo Arrieta Gunther,
Fort Lauderdale, FL (US); **Haney Awad**, Fort Lauderdale, FL (US);
Matthew David Swinton, San Francisco, CA (US); **Hayes Urban**, Saratoga, CA (US)

(73) Assignee: **Magic Leap, Inc.**, Plantation, FL (US)

(**) Term: **15 Years**

(21) Appl. No.: **29/717,272**

(22) Filed: **Dec. 16, 2019**

(51) LOC (13) Cl. **14-03**

(52) U.S. Cl.

USPC **D14/230**

(58) **Field of Classification Search**

(57) **CLAIM**

The ornamental design for device controller, as shown and described.

DESCRIPTION

FIG. 1 is a top perspective view of a first embodiment of the device controller.

FIG. 2 is a front view thereof.

FIG. 3 is a back perspective view thereof.

FIG. 4 is a left side view thereof.

FIG. 5 is a right side view thereof.

FIG. 6 is a top view thereof.

FIG. 7 is a bottom view thereof; and,

FIG. 8 is a bottom perspective view thereof.

The broken lines illustrate environmental features that form no part of the claimed design.

1 Claim, 5 Drawing Sheets
